PORTABLE RACK FOR STORING AND DISPENSING CANS

Clyde M. Combs, 2121 Virginia Ave. NW., No. 17,
Washington 7, D.C.

Filed June 19, 1961, Ser. No. 65,636

Term of patent 14 years

(Cl. D44—29)

FIG 3

FIG. 1 is a perspective view of a portable rack for storing and dispensing cans embodying my new design; FIG. 2 is a side elevational view thereof; and FIG. 3 is a top plan view thereof.

I claim:

The ornamental design for a portable rack for storing and dispensing cans, as shown.
